UNITED STATES PATENT OFFICE.

WILLIAM F. ULLRICH, OF WARREN, PENNSYLVANIA, ASSIGNOR, BY DIRECT AND
MESNE ASSIGNMENTS, TO ULLRICH PROPELLER COMPANY, OF WILMINGTON,
DELAWARE, A CORPORATION OF DELAWARE.

PROPELLING MECHANISM FOR BOATS.

1,283,984.

Specification of Letters Patent.

Patented Nov. 5, 1918.

Application filed July 13, 1916, Serial No. 109,109. Renewed March 26, 1918. Serial No. 224,890.

To all whom it may concern:

Be it known that I, WILLIAM F. ULLRICH, a citizen of the United States, residing at Warren, in the county of Warren and State 5 of Pennsylvania, have invented certain new and useful Improvements in Propelling Mechanism for Boats; and I do declare the following to be a full, clear, and exact description of the invention, such as will enable others skilled in the art to which it 10 pertains to make and use the same.

This invention relates broadly to improvements in propulsion mechanism for boats and the like, and its primary object is to 15 provide means of this character which is designed to permit two or more propellers to be driven on a single shaft.

An additional object is to provide means for revolving the propellers in opposite directions simultaneously.

Still another object is to provide an improved bearing upon which the propellers are rotatably mounted.

With these and many other objects in view, my invention resides in the novel features of construction, combination and arrangement of parts which will later be more particularly described and claimed.

In the accompanying drawings:—

30 Figure 1 represents a vertical longitudinal section through a portion of the vessel showing my improved propulsion mechanism applied thereto, the latter being in side elevation;

35 Fig. 2 is a central vertical longitudinal section of the parts shown in Fig. 1;

Fig. 3 is a vertical transverse section on the plane of the line 3—3 of Fig. 2; and Fig. 4 is a detail perspective view of one 40 of the retaining collars.

In this preferred embodiment, my invention comprises a plurality of propellers which extend below the bottom of a vessel and are operated by suitable gears mounted 45 upon shafts which extend parallel to the axis of the propellers. In the drawings, the numeral 1 designates the hull of a vessel provided with the usual longitudinally extending keel 2, the bottom of the vessel being provided with a flooring 3.

The propulsion mechanism is designed to be secured to said keel 2 at any preferred point thereon, and it consists of a tubular cylindrical axle 4, in the bore of which an

extension of said keel is disposed. A head 5 is formed at the forward end of the axle 4, and has its rear face at right angles to the longitudinal axle to provide a shoulder against which one of a number of propeller carrying rings 6 is adapted to bear. In the 60 present instance a pair of propeller carrying rings 6 is provided, the other ring being spaced from the first-mentioned ring which abuts the shoulder formed on the head 5, a spacing collar 7 being interposed 65 between said rings. In order to retain the ring 6, which is remote from the head 5, upon the axle 4, an additional collar 8 is fixed to said axle.

The rear straight side of the head 5, each 70 side of the collar 7, and the inner or forward face of the collar 8, are each provided with an annular ball race 9 in which a plurality of bearing balls 10 are disposed. The opposite sides of the rings 6 contact with 75 these balls 10, and are thus more readily revolved. The collars 7 and 8 may be fixed to the axle 4 by any preferred means, but are in the present instance held by pins 11 which extend entirely through the axle and 80 the keel 2 which is disposed in the bore of the latter.

In addition to the ball bearings which receive the end thrusts of the rings 6, roller bearings are also provided, these latter consisting of rollers 12 rotatably mounted in alined sockets 13 formed in the adjacent faces of the collars 7 and 8 and head 5. It will be noted from Fig. 2 that these rollers 12 are spaced from the periphery of the 90 axle 4 and that the rings 6 have an inner diameter slightly greater than the diameter of the circle inclosing said rollers 12. By providing both ball and roller bearings, the rings may be rotated with practically no 95 friction at all.

Each of the rings 6 carries a plurality of propeller blades 14, those on the forward ring being angled in a direction different from the angle of those on the rear ring. 100 Any number of propeller members may be provided on the axle 4, depending upon the size of the vessel to be propelled. It is advisable, however, to arrange the propeller members in pairs and rotate each alternate 105 member in a direction reversed to that of the others. To provide additional propelling members it is simply necessary to

lengthen the axle 4 and use additional collars in which the bearing elements may be mounted.

As a means for rotating the rings 6, each 5 is provided with gear teeth 15 which mesh with the teeth of the spur gears 16 and 16' operated by any preferred means, not shown, within the body of the vessel. The gear 16 is fixed on a shaft 17 that is disposed partly 10 parallel to the axle 4 and is rotatably supported in suitable brackets 18 mounted on the flooring 3. The other gear 16' is fixed to a tubular shaft 19 which surrounds and is rotated independently of the shaft 17. The 15 means which operates these drive shafts 17 and 19 causes the same to rotate in opposite directions, thereby causing the rings 6 with their blades 14 to also move in opposite directions. The gears 16 and 16' are continuously 20 in mesh with the gear teeth 15 of the rings 6 and extend through an opening in the flooring 3. In addition to being mounted on the keel 2, the axle 4 is also supported by suitable brackets 20 carried by the head 5 and the collar 8 and fixed to an adjacent portion of the vessel.

The operation of this propulsion mechanism is similar to that of other driving mechanism, in other words, to cause the 30 vessel to move forward the shafts 17 and 19 are caused to rotate in a suitable direction, and when it is desired to move rearwardly, these shafts must be rotated in the reversed direction. It is desired to lay particular emphasis upon the fact that as many 35 of the propelling members consisting of the rings 6 and blades 14, may be rotatably mounted upon the axle 4 as is necessary to propel the vessel at the required amount of speed.

Any preferred form of casing or housing 40 may be placed over the opening in the bottom of the boat through which the operating gears 16 and 16' extend, in order that the 45 water may be prevented from entering the hull of the vessel. This housing may be arranged so as to be readily removable to permit access to the gears or the propellers when necessary from the inside of the boat.

50 I claim:—

1. In a propulsion device of the class described, a central axle, a head on one end, a pair of spaced apart rings rotatable on said axle, a collar disposed between said rings 55 and fixed to said axle, an additional collar fixed at the end of the axle remote from said head, propeller blades on said rings, the blades of one ring being angled in opposite directions to those on the other, and means 60 for rotating said rings in opposite directions.

2. The combination with a vessel, of an axle having a central bore receiving the keel of said vessel, a ring rotatable on said axle, propeller blades on said ring, and means for 65 revolving said ring.

3. The combination with a vessel, of an axle having a central bore receiving the keel of said vessel, a pair of rings rotatably mounted on said axle, propeller blades carried by each of said rings, the blades of one 70 ring being angled in a reverse direction to those of the other, and means for rotating said rings in opposite directions.

4. The combination with a vessel, of an axle having a central bore receiving the keel 75 of said vessel, a pair of rings rotatable on said axle, a plurality of collars disposed on said axle to retain the rings thereon, pins extending through said collars and axle, said pins also being extended through said keel, 80 propeller blades on each of said rings, the blades of one ring being angled in the reverse direction to those of the other, and means for rotating said rings in opposite directions.

5. The combination with a vessel, of an axle having a central bore receiving the keel of said vessel, a plurality of rings rotatably mounted on said axle, a plurality of collars 90 fixed to said axle to space said rings from each other and retain the same on said axle, a plurality of propeller blades on each of said rings, the blades of the adjacent rings being angled in reverse directions, gear teeth carried by each of said rings, a tubular shaft, 95 a spur gear carried by said shaft, the teeth thereof meshing with the gear teeth of one of said rings, and an additional shaft rotatably mounted within the tubular shaft, and a spur gear fixed on said last-mentioned 100 shaft, the teeth thereof meshing with the teeth of the other of said rings, said spur gears being adapted to rotate in opposite directions to similarly rotate said rings.

6. In a propulsion device of the class described, an axle, a pair of spaced apart collar members fixed to said axle, a pair of sockets formed in the adjacent faces of each collar member, the sockets in one member being alined with those in the other, a roller in each alined pair of sockets, a ring rotatably mounted on said rollers, propeller blades on said ring, and means for rotating said ring.

7. In a propulsion device of the class described, an axle, a pair of spaced apart collar members fixed to said axle, the adjacent faces of said members each having an annular ball race therein, bearing balls in said ball races, the adjacent faces of said members also having a plurality of sockets therein, the sockets in one member being alined with those in the other, a roller in each alined pair of sockets, a ring rotatably mounted on said rollers, the sides of said ring engaging said balls, propeller blades on said 115 ring, and means for rotating said ring.

8. In a propulsion device of the class described, an axle, a head on one end of said axle, a pair of spaced apart collar members fixed to said axle and spaced from said head, 120

the adjacent faces of said members and said head each having an annular ball race formed therein, bearing balls in said ball races, the adjacent faces of said members and head 5 also having a plurality of sockets formed therein, the sockets in one of said faces being alined with those in the adjacent face, a roller disposed in each alined pair of sockets, a pair of rings rotatably mounted on 10 said rollers, one of said rings being disposed between the adjacent faces of said collar members and the other between the adjacent faces of one of said collar members and said

head, propeller blades on each of said rings, the blades on one ring being angled in a direction opposite to those on the other, and means for rotating said rings in opposite directions.

In testimony whereof I have hereunto set my hand in the presence of two subscribing 20 witnesses.

WILLIAM F. ULLRICH.
